UNITED STATES PATENT OFFICE.

WILLIAM P. THOMPSON AND ROBERT P. THOMPSON, OF PHILADELPHIA,
PENNSYLVANIA.

DESIGN FOR A RADIATOR.

SPECIFICATION forming part of Design No. 24,071, dated February 26, 1895.

Application filed September 18, 1894. Serial No. 523,433. Term of patent 14 years.

To all whom it may concern:

Be it known that we, WILLIAM P. THOMPSON and ROBERT P. THOMPSON, citizens of the United States, residing at Philadelphia, Pennsylvania, have invented and produced a new and original Design for Radiators for Heating Air, of which the following is a specification, reference being had to the accompanying perspective drawing thereof.

10 The leading feature of this design consists in a radiator provided with projecting parallel continuous webs marked 1 and 2, on the tubes 3 and 4 and on a connecting tube 5 so disposed that the webs 1 on the upper tube 3 and the upper part of the tube 5 are above the spaces between the webs 2 on the lower

tube 4 and the lower portion of the tube 5 and the webs on one side of the upper tube 3 are in the same plane as the webs on the opposite side of the lower tube 4, so that in any position, the same relative position of webs is presented to the eye of an observer. The tubes 3 and 4 have openings 6 and 7 at the end opposite the tube 5.

What we claim is—

25 The design for a radiator as herein shown and described.

WM. P. THOMPSON.
ROBT. P. THOMPSON.
